REFLECTOR SIGN

William H. Rapp, New Rochelle, N. Y.

Application February 6, 1940, Serial No. 317,487

4 Claims. (Cl. 40—142)

This invention relates to new and useful improvements in reflector signs used for numbers and name plates and particularly intended for interior and exterior signs, and for highway signs, railroads, crossing markers, billboard advertisements, and other general exterior and interior sign purposes. The invention also contemplates the use of recessed letters, numbers or figures arranged in a particular manner presenting reflecting letters, numerals or figures, as desired.

The invention has for an object the construction of an article as mentioned which is characterized by a flat rigid plate upon which numbers and letters may be secured. The invention proposes a simple and efficient way of supporting the rigid plate on the ground or projecting from walls, doorways or other places.

The invention further contemplates constructing the letters, numerals or figures in a certain manner so as to obtain the recessed and reflecting effect mentioned.

Still further the invention contemplates the association of a reflector with the rigid plate to reflect light from the vicinity and so call attention to the sign.

Still further the invention proposes a novel way of securing numbers and letters upon the rigid plate.

The invention contemplates constructing the rigid plates in several sizes for accommodating more or less letters or numbers, as a particular job may require.

Furthermore, the invention proposes the provision of brackets of various sizes and suitable supporting mechanism for supporting the rigid plates mentioned.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a fragmentary front elevational view of a sign constructed according to this invention and illustrated with the numbers or letters mounted thereon.

Fig. 2 is a central vertical sectional view of the sign shown in Fig. 1.

Fig. 3 is a fragmentary front elevational view of a sign constructed in accordance with a modification of this invention.

Fig. 4 is an end elevational view of the sign shown in Fig. 3.

Fig. 5 is a fragmentary front elevational view of another sign constructed in accordance with another form of this invention.

Fig. 6 is an end elevational view of Fig. 5.

Fig. 7 is an elevational view of a sign constructed in accordance with another form of the invention.

Fig. 8 is a schematic elevational view of a sign or marker arranged in accordance with another modified form of this invention.

Fig. 9 is a fragmentary elevational view of a sign constructed according to another form of the invention.

Fig. 10 is an enlarged detailed view of a portion of the rigid plate shown in Fig. 9, to disclose details of one of the rivets and its mounting.

Fig. 11 is a vertical sectional view taken on the line 11—11 of Fig. 10.

Fig. 12 is a fragmentary front elevational view of a sign constructed in accordance with another modification of this invention.

Fig. 13 is a vertical sectional view taken on the line 13—13 of Fig. 12.

Fig. 14 is an end view of the rigid plate used in Fig. 12.

Fig. 15 is an edge elevational view of a numeral constructed in accordance with this invention and intended to be used in the sign.

Fig. 16 is a front elevational view of the back plate of the numeral shown in Fig. 15.

Fig. 17 is a front elevational view of the face plate and reflecting plate of the numeral shown in Fig. 15.

Fig. 18 is an elevational view of a half sized spacer constructed in accordance with the form of the invention illustrated in Fig. 12.

Fig. 19 is a partial sectional view of the tubular rivet used in this device.

Fig. 20 is a front elevational view of a reflector plate.

The sign for numbers and letters, in accordance with the form of the invention illustrated in Figs. 1 and 2, includes a rigid plate 12, preferably of hot rolled steel sheet material adapted to receive and support numbers and letters as hereinafter more fully described. A bracket 13 is mounted upon one side of the plate 12 and is connected with a suitable support for supporting the sign. This bracket has a bottom socket portion 13a into which a vertical rod 14 is mounted.

This rod forms a part of the support. The rod 14 may be solid or hollow. At its lower end it is provided with a cap 15. The cap 15 is engaged in 55

between the arms of a horizontal channel member 16, or the cap can be eliminated by brazing or welding rod 14 to the channel or flat strip of metal.

5 A self-tapping screw or other fastening element 17 secures the cap 15 to the channel 16. The cap 15 may also be welded or brazed to the channel member to more rigidly connect these parts. Another channel 18 is extended at right angles across the bottom of the channel 16. The screw 17 is engaged through the central portion of the channel 18 to secure this channel to the channel 16. Moreover, the joint may be reinforced by welding or brazing.

15 The upper end of the rod 14 is provided with threads 14^a which are threadedly engaged into the portion 13^a of the bracket 13. The bracket 13 has a top portion 13^b which is disposed across the top of the portion 13^a at right angles thereof. 20 This top portion 13^b has a slot 20 into which a tab portion 12^a formed on the edge of the rigid plate 12 engages. The tab portion 12^a may be securely held connected with the bracket 13 by fastening elements engaging into openings 21 formed in these parts.

25 Another bracket 23 is mounted on another side of the plate 12. This bracket 23 engages a tab portion 12^b formed on this edge of the rigid plate 12. Fastening elements may engage through openings 24 formed in the adjacent material of the bracket 23 and tab 12^b, to rigidly connect these parts together. The bracket 23 has a horizontal tubular portion 23^b adapted to receive reflector buttons, reflecting glass or Lucite members, or the like.

30 Various numbers or letters to form a name plate, or the like, may be mounted upon the rigid plate 12. These letters and numbers may be secured in place by rivets, fastening elements, or the like as hereinafter more fully described relative to the other forms of this invention, which show letters and numbers applied.

35 This particular sign may be used by embedding the lower portion of the rod 14 into the ground so that the channels 16 and 18 are also in the ground and serve to firmly hold the rod 14 in a vertical position. The reflectors which are proposed to be mounted on the bracket 23 will reflect light from the vicinity, and call attention 40 to the sign.

45 In Figs. 3 and 4 another embodiment of the invention has been disclosed which is very similar to the prior form. In this form there is a flat rigid plate 12' of a shorter length than the plate 12 illustrated in the prior form. This plate 12' has numerals 25 mounted on the front and rear faces thereof. Each of these numbers is secured by top and bottom rivets 26. These rivets are preferably made of two portions 26^a and 60 26^b. Portion 26^a is tubular and is adapted to receive the stem portion 26^b which may be forced into the hollow of member 26^a and held therein frictionally at any set position. These rivets are so arranged that each rivet assists in securing the numbers 25 on each of the sides of the plate 12'. The plate 12' must be drilled or punched with suitable openings for the rivets 26. Preferably, the rivets 26 should be of tubular form formed from two sections which may be hammered together.

65 A bracket 23 is mounted upon a top tab 12^b of the plate 12'. This bracket 23 supports the reflectors 28. The plate 12' is supported at the bottom by a bracket 13' which is mounted upon 70 the top of a rod 14'. In other respects this form

of the invention is similar to the previous form.

In Figs. 5 and 6 another form of the invention has been disclosed which is similar to the previous form, distinguishing merely in the fact that this sign is composed from a flat rigid plate 12'' supported upon a bottom bracket 13'', which in turn is supported upon a vertical rod 14''. A top bracket 23 is mounted on the plate 12'' and is provided with a front reflector lens 28. The back of the bracket 23 is closed with a plug 30. Letters 31 are mounted on the front face of the plate 12'' by the use of rivets 32. In other respects this form of the invention is similar to the previous forms.

15 In Fig. 7 another form of the invention is disclosed which is similar to the prior forms, distinguishing merely in the fact that the rigid flat plate 12 is supported by a bracket 13 secured to one side. This bracket is connected with a wall flange 33 supported on a wall 34. At the outer 20 end the plate 12 is provided with a bracket 23 supporting reflectors 28. The letters or numbers to form the sign should be mounted on the front and back faces of the plate 12. In other respects this form of the invention is similar to the previous forms.

25 In Fig. 7 wall flange 33 may be eliminated and bracket 13 screwed into a T or fitting fastened to rod 14 to be hung over hedges, walls, etc.

30 One face plate on both or either sides of rigid plate 12'' covering the entire surface with necessary cutouts or stampings as required for letters, numbers or figures is fastened by soldering, brazing or welding to the rigid plate. The reflecting material is placed between both plates 35 before fastening method is made, thus forming a complete solid unit. The tubular rivets may be substituted in place of brazing, welding, etc., forming a continuous face surface with one face plate.

40 Springs can be fastened to back plate of letters, numbers, or figures by soldering, brazing, or welding, and when so fastened no slot or hole is necessary for face or back plate of letters, numbers or figures. The tensioned leaf spring holds 45 firmly the letters, etc., against rigid plate while track channels keep letters, etc., in position. The letters, numbers, and figures can be removed or adjusted as desired.

45 The tubular rivets described herein are also to be used to fasten plain, recessed letters, numbers and figures of reflecting materials or other materials of plain or raised surfaces. These materials of various thicknesses are to be used on existing signs.

55 Holes may be drilled or punched in the metal, Lucite or other reflecting materials which will permit the glass or Lucite portion of the reflector lens unit of clear crystal or of any other color to protrude beyond the reflecting surface, thus increasing the reflectivity. The body of the reflector lens unit is inserted in the back plate which may be of variable thickness.

60 In Fig. 8 still another embodiment of the invention has been disclosed distinguishing from the prior form in the fact that a pipe fitting 35 is supported on a vertical rod or pipe 36 which is mounted in the ground 37. The lower end of the pipe 36 is provided with a pair of crossing channels 38 and 39 to form a suitable foundation. 70 Reflector lenses or the like may be mounted in the side ends of the pipe fitting 35. This pipe fitting may be of various designs and shapes, depending merely upon taste.

75 In Figs. 9 to 11 inclusive, still another form of

the invention is disclosed distinguishing from the prior forms in an arrangement whereby the letters may be suitably spaced upon the supporting plate 12". According to this form of the invention the rivets 32 which are used to support the letters 31 are formed from two sections. There is a rear section 32^a having a tubular shank which is engaged by a solid shank of a front section 32^b. These rivets pass through elongated slots 40 formed in the material of the plate 12". Each slot 40 is provided with a leaf spring 41 which has a longitudinal portion 41^a extending substantially the length of the slot, and end portions 41^b engaging the material of the plate 12" for supporting the leaf spring in position. With this arrangement it is possible to shift the letters 31 laterally, in either direction as limited by the length of the slots 40. Thus it is possible to properly space the letters in relation to each other. Once the letters are suitably spaced the sections of the rivets may be hammered down very tightly to frictionally hold the letters in adjusted positions.

In Figs. 12 to 18 inclusive another modified form of the invention is disclosed. The sign herein includes a rigid plate 12, preferably of hot rolled steel sheet material adapted to receive and support numerals and letters as hereinafter more fully described. A bracket 13 is mounted upon one side of the plate 12 and is connected with a suitable support for supporting the sign. This bracket has a bottom socket portion 13^a into which a vertical rod 14 is mounted. This rod forms a part of the support. Another bracket 23 is mounted on the other side of the plate 12. This bracket 23 has a horizontal tubular portion 23^b supporting reflectors 28.

Opposed pairs of tracks 45 are mounted on each of the faces of the plate 12 and are adapted to support letters and numbers. Each track 45 has a portion 45^a mounted upon and projecting at right angles from the plate 12, and a portion 45^b projecting at right angles to the portion 45^a. A space 46 is thus formed between each portion 45^b and the adjacent portion of the plate 12. In this space the letters and numerals are supported.

Each letter or numeral is formed from several layers or sheets of material. Each has a back plate 47 which is of a height to slip in between opposed spaces 46 of the tracks on one side of the plate 12. A face plate 48 is formed with cut out portions 49 forming the numeral or letter. A reflecting sheet 50 is mounted upon the back of the face plate 48. These parts may be secured together with cement, or in any other manner, such as welding, brazing or the like. Certain of the numerals or letters, are of designs having an island portion, such as the portion 49^a. This portion is mounted on the reflecting sheet of the plate 40. The plates 47, 50 and 48 are secured together as a unit. This may be accomplished with Glyptal cement, or by brazing, welding, soldering or other methods.

The integrated numeral, letter or figure unit is ground and sanded to a smooth finish. The reflecting sheet which is visible through the cut-outs of the facing plate is then covered with a suitable masking paste or other protective material, and then the complete unit is given a siccative coating with protective material. The unit may then be placed in an oven and baked, or an air dry finish may be applied without baking. After the siccative coating is dry, the masking paste or other material is then removed with water or other solvents and dried with warm air.

The sheet 50 may be of any desired reflecting material and design and may also be substituted by a suitable non-reflecting surfaces.

Each of the individual plates of the unit is formed with a slot 51 or hole which may be punched in or drilled in the plates along its top and bottom portions. In the completed unit these slots are superimposed, as shown in Fig. 15. The unit is mounted on the plate 12 by slipping it inwards upon the tracks from one of the open ends. Then rivets or other fastening elements 52 are engaged through the portions 45^b of the tracks and the plate 12 and through the openings 51 of the unit to hold the unit in position. The ends of the sign are closed with half sized spacers 53. These spacers may comprise several sheets of material, or one sheet of material, of a suitable thickness to slip into the ends of the tracks 45. The spacers are fixedly held by rivets 52 which are engaged through the material of the tracks 45, the plate 12 and the spacer 53.

In Fig. 20 a reflecting plate 50' is illustrated with reflector lens 51. This type of reflecting plate with any number of suitably arranged reflector lens may be used in connection with the device.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a sign used for numbers and name plates, a flat rigid plate for numbers and letters, and numbers or letters mounted on said plate, said letters or numbers being secured with rivets engaged through openings therein and extending through horizontal elongated openings in said plate, leaf springs mounted in said elongated openings and abutting said rivets for frictionally holding the rivets in adjusted positions, and each rivet being formed from a front section and a rear section adapted to be tightly driven together after the letters have been properly adjusted for fixedly holding them.

2. In a sign used for numbers and name plates, a flat rigid plate formed with laterally extended elongated slots, numbers or letters for engagement on said plate, said numbers or letters being formed with apertures in aligned positions with said slots, rivets freely engaged through said aligned apertures and slots, whereby said numbers and letters may be shifted with relation to each other to properly space said numbers or letters on said plate, and means on said plate for temporarily holding said numbers or letters in their adjusted positions.

3. In a sign used for numbers and name plates, a flat rigid plate formed with laterally extended elongated slots, numbers or letters for engagement on said plate, said numbers or letters being formed with apertures in aligned positions with said slots, rivets freely engaged through said aligned apertures and slots, whereby said numbers and letters may be shifted with relation to each other to properly space said numbers or letters on said plate, and means on said plate for temporarily holding said numbers or letters in their adjusted positions, comprising leaf springs extended parallel to said slots and mounted on

said plate and engaging said rivets to limit sliding.

4. In a sign used for numbers and name plates, a flat rigid plate formed with laterally extended elongated slots, numbers or letters for engagement on said plate, said numbers or letters being formed with apertures in aligned positions with said slots, rivets freely engaged through said aligned apertures and slots, whereby said num-

bers and letters may be shifted with relation to each other to properly space said numbers or letters on said plate, and means on said plate for temporarily holding said numbers or letters in their adjusted positions, said rivets being adapted to be tightly driven together for securely holding said numbers or letters in position on said plate after having been properly positioned.

WILLIAM H. RAPP.
